(57) **CLAIM**

The ornamental design for an electric vehicle charger, as shown and described.

DESCRIPTION

FIG. 1 is a perspective view of an electric vehicle charger; FIG. 2 is a front view of the electric vehicle charger; FIG. 3 is a rear view of the electric vehicle charger; FIG. 4 is a right side view of the electric vehicle charger; FIG. 5 is a left side view of the electric vehicle charger; FIG. 6 is a top view of the electric vehicle charger; FIG. 7 is a bottom view of the electric vehicle charger; FIG. 8 is an enlarged front view defined by the ranges A-A and B-B of FIG. 2; FIG. 9 is an enlarged cross-sectional view defined by the ranges D-D and E-E of FIG. 6, and range M-M of FIG. 4, and taken along line C-C of FIG. 8; FIG. 10 is an enlarged top view defined by the ranges D-D and E-E of FIG. 6; and, FIG. 11 is an enlarged perspective view defined by the ranges X-X and Y-Y of FIG. 1.

The broken line showing of a body, a connector and an electric cable is for the purpose of illustrating unclaimed portions of the electric vehicle charger and forms no part of the claimed design.

1 Claim, 11 Drawing Sheets
